UNITED STATES PATENT OFFICE.

GEORGE H. KITCHEN, OF NEW YORK, N. Y.

TRANSPARENT SIGN.

SPECIFICATION forming part of Letters Patent No. 313,343, dated March 3, 1885.

Application filed January 3, 1884. (No model.)

To all whom it may concern:

Be it known that I, GEORGE H. KITCHEN, of the city, county, and State of New York, have invented a new and Improved Transparent Sign, of which the following is a full, clear, and exact description.

My invention relates to that class of signs where glass "bull's-eyes" are used to form the transparent letters of the sign, the sign being adapted to be placed over a gas or other light.

Reference is to be had to the accompanying drawings, forming a part of this specification, in which similar letters of reference indicate corresponding parts in all the figures.

Figure 1 is a front elevation of a part of a sign made in accordance with my invention. Fig. 2 is a rear elevation of a part of the metal portion or body of the sign and one of the bull's-eyes, showing the method of securing the bull's-eye in place. Fig. 3 is a sectional elevation of the same taken on the line $\alpha\alpha$ of Fig. 2; and Fig. 4 is a sectional elevation of the old form of bull's-eye.

Heretofore in making transparent signs where glass bull's-eyes have been used the bull's-eyes have been formed, as shown in Fig. 4, with the shank s of smaller diameter than the outer surface or edge of the bull's-eye, and of smaller diameter also than the cavity of the bull's-eye. The first objection to this is that the light within the sign is obstructed by the body portion t of the sign surrounding the shank s , so that the full outline of the bull's-eye is not visible from the outside of the sign; and the second objection is that the cavity e of the bull's-eye, being of greater diameter than the shank s , forms a pocket, e' , within which dust soon collects, which obscures the transparency of the bull's-eye and renders frequent cleaning of the sign a necessity.

My invention consists in forming the bull's-eye with a lip or flange of greater diameter than the visible outline of the bull's-eye, thus making it practicable to form a very shallow cavity in the bull's-eye, and adapting the bull's-eye to be placed in the body of the sign from the inside thereof, so that no portion of

the ornamental outline of the bull's-eye will 50 be obscured by the body portion of the sign, and so that no dust can collect and remain within the bull's-eye.

A represents the body of my new and improved transparent sign, and B represents the 55 improved glass bull's-eye of the sign.

The body A is by preference made of sheet-iron. In this instance the bull's-eyes B are made star-shaped; but they might be made, if desired, of any other ornamental outline, 60 and they are each formed with the shallow cavity a and with the circumferential lip or flange b , which is set back from and at right angles to the shoulder c , which latter gives the true ornamental outline of the bull's-eye, 65 and when in place in the sign protrudes from or projects through and beyond the outer surface of the body A, as will be understood from Fig. 3.

In forming the sign with the star-shaped 70 bull's-eyes B the body A is first cut with star-shaped openings d , of a size to just receive the shouldered outline portions c of the bull's-eyes. Then the bull's-eyes B are placed in the openings d from the inside or rear of 75 the sign and secured by the lips f , formed upon or secured to the inner surface of the body A, as will be understood from Figs. 2 and 3.

Constructed in the manner described, it will 80 be seen that no dust can collect and remain in the bull's-eye to obscure its transparency, that the full ornamental outline of the bull's-eyes will always show from the outside of the sign, and that the method of placing and holding the bull's-eyes in the body A is perfectly 85 practical and renders the sign cheap and durable.

Having thus described my invention, I claim as new and desire to secure by Letters Patent— 90

1. The transparent sign herein shown and described, consisting of the body A, formed with the openings d , of a size and shape to correspond with the shouldered outline portion c of the bull's-eyes B, in combination 95 with the said bull's-eyes passed through said apertures from the rear, and formed with said shouldered outline portion c on its front face,

and with the circumferential flange or lip *b* in rear of and at right angles to the shouldered portion *c*, to form a bearing to rest against the rear face of the body *A*, as described.

5 2. As a new article of manufacture, the ornamental bull's-eye *B*, formed with the shouldered outline portion *c* on its front face, cir-

cumferential flange or lip *b* in rear of and at right angles to the shouldered portion *c*, and shallow recess *a* in the rear face, as described.
